UNITED STATES PATENT OFFICE

MARCUS S. LEVE, OF SAN FRANCISCO, CALIFORNIA, ASSIGNOR TO PACIFIC CAN COMPANY, OF SAN FRANCISCO, CALIFORNIA, A CORPORATION OF NEVADA

MACHINE FOR LINING CAN ENDS WITH A SEALING COMPOUND

Application filed March 12, 1932. Serial No. 598,386.

This invention relates to improvements in machines for lining can ends with a sealing compound, and especially to a machine adapted interchangeably to apply lining compound to flanged can ends of both circular and non-circular contour, like oval, square, rectangular or irregular shaped.

One of the objects of this invention is the provision of a machine for applying lining compound to a can end flange, whatever the contour or shape of the end may be.

Another object of the invention is the provision of a machine of this character, which may be readily converted from an arrangement accurately lining a can end of one shape, into an arrangement for lining an end of an entirely different shape.

Another object of the invention is the provision of automatic means preventing the opening of the compound nozzle, when a can end has not been delivered to receive the compound.

A further object of the invention is the provision of a manual control mechanism whereby the opening of the compound nozzle may be prevented, whether there was or was not a can end delivered.

With these objects in view the machine is furnished with a can end magazine, where the can ends are piled by hand or otherwise in a stack, and an automatic feeding device is provided for removing the lowermost can end in the stack, delivering it upon a lower chuck, mounted upon the end of a swinging arm. The lower chuck, supporting the can end, is then elevated for a short distance, and brought into engagement with an upper chuck, carried upon the end of another arm, clamping the can end between them.

Rotary motion for one and one half revolutions is then given the chuck and can end, and then they are brought to a stop and lowered to the original elevation.

A nozzle adapted to discharge sealing compound is stationarily secured above the chuck and furnished with a needle valve, adapted to be raised from its seat and discharge sealing compound into the curled flange of the can end, soon after the chuck started to ro-

tate, and then to be lowered upon its seat and stop the discharge of the compound, before the rotation of the chuck stops. The needle valve keeps the nozzle open for somewhat more than one complete revolution of the chuck.

Means are provided to swing the chuck carrying arms towards and away from the nozzle, during the rotation of the irregular shaped can end, so as to keep the center line of the curled flange under the discharge tip of the nozzle.

After the chuck has been lowered, the automatic feeding device removes the lined can end from the chuck, delivering it upon a discharge conveyor; and at the same time places another can end upon the chuck, carrying it from the can end magazine.

The following description with reference to the accompanying drawings forming part of this specification discloses one preferred embodiment of the invention.

Figure 1 of the drawings is a side elevation of the machine.

Figure 2 is a plan view of the same.

Figure 3 is a sectional elevation of the machine taken on line 3—3 of Figure 2.

Figure 4 is a sectional plan taken on line 4—4 of Figure 3.

Figure 5 is a vertical cross section of the machine drawn to a larger scale, and taken on line 5—5 of Figure 2.

Figure 6 is a detail of the upper and lower chucks carried upon the swinging arms, and of the mechanism for rotating the spindle and the lower chuck, and for raising and lowering the same, showing also the feeding devices for preventing the discharge of lining compound from the nozzle, if there is no can end to receive it.

Figure 7 is a plan of the table, showing the can end feed mechanism.

Figure 8 is an enlarged detail, showing a can end releasing bar in cross section and the separating and supporting knives.

Figure 9 is a side elevation of a releasing bar, carrying the separating and supporting knives, showing said releasing bar in its proper relative position to the base plate drawn in section.

Referring to the drawings in detail, 1 indicates the frame of the machine, on which is supported a table or top 2. A can end magazine 3, provided with the guiding rods 4, and 5 adapted to support and guide a stack of can ends 5, is secured upon the table.

The can end magazine consists of the base plate 51, provided with an opening 52 of the form and size, corresponding with the form 10 and size of the can ends, and of the guiding rods 4 secured to said base.

A recess 53 is cut on the lower face of the base, as shown in figures 2 and 8, and within said recess are fitted to slide the can end feed 15 slide 54, and the can end releasing bars 55.

The purpose of the can end feed slide 54 is to move a can end, released from the stack 5, and place it upon a chuck 22; and to remove a can end from the chuck, and place it upon a 20 discharge conveyor 91; while the purpose of the releasing bars 55 is to separate the lowermost can end from the rest of the stack, and drop it upon the surface of the table.

The feed slide 54 is adapted to slide upon 25 the surface of the table 2, being guided by the guides 92; it is driven by a crank 58, secured upon the vertical shaft 48, and connecting by means of a link 59 with a pin 60, carried by the slide 54.

30 The can end feed slide is made with two prongs 65 and 66, and is formed with the shoulders 93 and with the lugs 94, the former engage a can end, dropped upon the table by the releasing bars 55, and deposit it upon the chuck 22, while the latter engage a can end 35 upon the chuck 22, and deposit it upon the conveyor 91.

The releasing bars 55 are placed next above the feed slide 54; they are two in number, and 40 are situated one on each side of the slide. They are formed with the upturned lugs 56 and 57, and are adapted to slide longitudinally, being guided in the recess 53.

The releasing bars are held normally by 45 the springs 61 in the position at the extreme forward end of their travel, resting with the set screws 63, carried upon the lugs 57, in contact with the base plate 51, and are moved in the opposite direction against the action 50 of the compression springs 61 by the set screws 62, carried upon posts 64 near the ends of the prongs 65 and 66 of the feed slide 54, when said slide moves towards the can end stack, and return to the normal position at 55 the beginning of the forward stroke of the slide.

Each of the releasing bars is provided with a separating plate 95, and with supporting plates 96, the said plates are formed with the 60 knife edge projections 97 and 98 which extend within the opening 52 of the base plate 51.

The knife edge 97 is located forwards of the knife edge 98, and is placed above it at a distance equal to the thickness of a can end as 65 shown in Figure 8.

When the slide 54 is moving in a direction from the discharge conveyor towards the can end magazine, the releasing bars 55 remain at their normal position, and the can end stack is resting upon the lower supporting knife edges 98, the separating knife edges 97 being forwards of the stack; upon the approach of the slide 54 towards the stack 5, the releasing bars 55 move with the slide, the separating knife edges 97 entering the stack next above 70 the lowermost can end, leaving said can end rest upon the supporting knife edges 98, while the rest of the stack becomes supported by said separating knife edges 97; at a short distance before the end of travel of the releasing bars in the direction from the discharge conveyor towards the stack, the supporting knife edges 98 move out from beneath the lowermost can end, letting it drop upon the surface of the table, to become engaged by the 75 can end feed slide 54, upon its next forward stroke, and to be carried to the chuck 22.

Upon the forward stroke of the slide 54 the releasing bars follow the slide forwards, being driven by the springs 61. On the forward motion of the bars the supporting knife edges 98 enter beneath the stack, before the separating knife edges 97 move out from beneath it, letting the stack drop upon the supporting knife edges 98; in this manner 80 the can ends are separated and removed one by one from the bottom of the stack and placed upon the chuck 22.

The chuck 22 is adapted to rotate in a horizontal plane, is capable to move for a short 100 distance up and down, and has a swinging motion in a horizontal plane together with a bifurcated swinging lever, upon the end of which it is mounted.

At one side of the machine there are secured the bearings 10 and 11, within which a vertical tubular shaft 12 is mounted, the upper end of which extends for some distance above the upper bearing 10, where an arm 30 is keyed. Below the bearing 10 the tubular shaft 12, carries a bifurcated arm, comprising the long hub 16, and the upper and lower prongs 17 and 18.

The bifurcated arm is also keyed to the tubular shaft 12, being in alignment with 115 the arm 30.

Bearings 19 and 20 are provided on the prongs 18 and 17, within which a spindle 21 is mounted; said spindle extending above the bearing 20, where the lower chuck 22 is keyed, and extending below the lower bearing 19, where a spur gear 23 for rotating the spindle 21 is secured; below the gear 23 a surface cam 24, having an outline corresponding to the shape and size of the cam end, is fastened.

For imparting a swinging motion around the center of the tubular shaft 12 to the bifurcated arm, a bracket 25 is secured to the frame of the machine, and a plate 26, 130

carrying a pin 27, upon which is mounted a roller 28, is fastened to said bracket 25, and a tension spring 29, secured at one end to said arm and at the other end to a stationary cross plate 73, keeps the surface cam 24 in constant contact with said roller 28; the rotation of the cam 24 causing the swinging of the arm, the tubular shaft 12 oscillating within the bearings 10 and 11.

10 The arm 30 is furnished with a bore 31, arranged in vertical alignment with the spindle 21, and within said bore a sliding sleeve 34 is fitted; and within said sleeve a tubular stem 33, carrying the upper chuck disc 32 is mounted; a thrust ball bearing 35, and an annular ball bearing 36 being interposed between said stem and said sleeve.

15 The sleeve 34 is provided with a flange 37, fitting inside the bore 31 at the bottom, while a gland 38 screwed into the upper part of the bore 31 guides the sleeve at the top, and a helical spring 39 surrounds the sleeve, engaging at the top the gland 38, and pressing at the bottom against the flange 37, keeping the sleeve normally in a downward position, the flange of a gland 69 which secures the outer race of the annular ball bearing 36 to the sleeve, serving as a stop.

20 The upper chuck 32 is thus held down 30 yieldingly by the helical spring 39, and rotates with little resistance.

25 The mechanism for raising and lowering the spindle 21 together with the lower chuck 22 consists of a forked lever 110 pivoted at 35 111 to the hub 16 of the bifurcated lever, and engaging at the free forked end a block 112, fitted upon the spindle 21, and held in place by the collars 113, and of devices for actuating said forked lever; the said devices are 40 a cam 114, secured upon the main driving shaft 40 of the machine, engaging a roller 115 carried upon the end of one arm of a bell crank lever 116, the other arm engaging a roller 117, carried upon the lower end of a 45 rod 118 connecting with said lever.

30 The machine is driven from the main driving shaft 40, carrying the spur gear 42, which meshes with an idler spur gear 43, revolving upon a pin 44, and transmitting motion to 50 a spur gear 45, keyed to the driven shaft 41. The gear 42 of the driving shaft and the gear 45 of the driven shaft are of the same diameter and pitch of teeth, and cause the driven shaft 41 to turn with the same rate of 55 speed as the driving shaft 40. The driven shaft 41 carries a miter gear 46, transmitting continuous motion to a similar miter gear 47, keyed to the vertical can end feed shaft 48, while a spur gear 49, keyed at the lower 60 end of the vertical shaft 48, and meshing with a similar gear 89, carried upon the vertical drive shaft 50, transmits continuous motion to said shaft.

35 The driving shaft 40, the driven shaft 41, the vertical can end feed shaft 48, and the

vertical drive shaft 50 all revolve continuously and at the same rate of speed, making one complete revolution, each time a can end has been lined with lining compound, and the can end feed slide 54, driven by the vertical shaft 48, reciprocates also continuously, making a stroke forwards and back again, each time a can end is lined, the other devices in the machine are so timed, as to conform to the motion of said slide. 75

For imparting an intermittent rotation to the spindle 21 of the lower chuck 22 the following mechanism is used.

The vertical can end feed shaft 48 is mounted at the lower end in a bearing 70, provided upon the cross plate 71 of the frame, and at the upper end in a bearing 72, carried upon a cross plate 73 of the frame.

20 A spider 74, provided with a long hub, is fitted to revolve freely around the shaft 48 and is driven intermittently from the short vertical shaft 50, by the devices herein described; the spider connects by a chain of gears with the spindle 21 of the chuck 22, causing its rotation, and it is desired that said rotation be uniform during the time lining compound is discharging into the curled flange of the can end, in order to distribute the compound more evenly; and it is also desired, that the starting and stopping of the rotation of the chuck be gradual in order to insure the smooth working of the machine. 95

25 The device here used fulfills the above stated requirements, it is of the nature of a Geneva cam, as it also transforms a continuous rotary motion of one member into an intermittent motion of another, but differs in the nature of the motion produced. The rate of acceleration at the starting and of deceleration at stopping in this device is such as to take up a small part of the motion, leaving the middle portion of uniform speed, while in the resultant motion of a Geneva cam, there is no middle portion of uniform speed, it is all accelerating, or decelerating. 100

30 The spider 74 in this case is formed with six arms, and its rotation for one sixth part of a revolution at a time is transmitted to the spindle 21 by means of the gear 75, secured upon the hub of the spider 74, engaging a pinion 76 on a vertical idler shaft 77, mounted in the bearings 78 and 79 at the side of the frame of the machine, while a larger gear 80, secured upon the idler shaft 77, meshes with the gear 13, loosely mounted upon the tubular shaft 12, imparting motion to it and to the gear 15, keyed upon the hub 14 of said gear 13. 115

35 The gear 15 meshes with an intermediate gear 81, which in turn engages the gear 23, keyed to the spindle 21, and causes its rotation. 120

40 The ratio of gearing between the spider gear 75 and the gear 23 of the spindle is such, as to cause said spindle to revolve for 130

one and one half of a revolution, each time the spider revolves for one sixth of a turn.

For transmitting intermittent motion to the spider 74 from the vertical shaft 50, there are provided a plurality of antifriction rollers 82, mounted upon pins on the lower face of the spider, one on each arm, placed at equal distances from the center, and equally spaced one from the other; below the spider is placed a disc 83, furnished with a hub 84, whereby it is keyed to the shaft 50, and upon said disc is secured a flat cam 85, having an outline of such a shape, as to enter between two adjacent rollers, and be in contact with both of them during the rotation of the spider, the constant contact prevents any back lash in the spider, giving it a smooth motion.

The ratio of the time the spider is in motion to the time it is at rest depends upon the distance between the shaft 48 and the shaft 50, and the rate of acceleration at starting, and deceleration at stopping, depends upon the curvature at the portion of the cam at both ends of its center line; the sharper the curves, the more rapid the acceleration.

Since said curvatures may be varied in different cams, the desired rate of acceleration of the spider may be obtained, by giving the proper curve to the cam.

In the machine illustrated, the spider 74 is moved for a distance of one sixth of a revolution, during the rotation of the driving shaft 50 through an angle of 110° and during the remaining 250° , the spider is at rest in order to give time for the lowering of the lower chuck 22, for removing a can end from said chuck, for withdrawing a can end from the bottom of the stack and place it upon the chuck, and for lifting the lower chuck 22 and bring it in contact with the upper chuck disc 32, in order to clamp the can end.

In determining the distance required between the said shafts 48 and 50, it may happen, as in this case, that the center of the shaft 50 comes close to the path of travel of the roller 82. When the roller is in the position shown at 90 in Figure 4, the point of contact of the cam surface with the roller being near the center of the shaft 50, said point of contact has little motion, and in order to move the roller with the required speed, it has to press upon the arm of the spider in a direction too close to a radial line, thus subjecting the roller pin to an excessive strain; to avoid this strain, a roller 86 is mounted upon a pin 87, carried upon the cam 85, and cam surfaces 88 are formed upon the arms of the spider. The roller 86, having more motion, engages the cam surfaces 88 at more favorable angles, taking away the load from the rollers 82, and moves the spider for some distance, until said rollers are far enough away from the center of

the shaft 50, when the cam surface 85 acts upon them in a more favorable direction.

The cam illustrated gives an accelerating motion to the spider during 9° rotation of the same, then moves it for a distance of 42° at a uniform speed, and at last brings it to rest within 9° of motion.

It is evident, that this can not be accomplished by a Geneva movement.

The rotation of the spider for a distance of 60° around the vertical shaft is transmitted to the spindle 21, causing it to make one and one half revolutions, the middle portion amounting to more than one complete revolution being of uniform motion, and the rest variable.

Above the table, adjacent the can end magazine, is secured a nozzle 6, containing lining compound under pressure; the nozzle is held within the bore of a bracket 7, mounted upon the table.

The nozzle is furnished with a needle valve, provided with a stem 8, whereby it may be raised off its seat in the tip 9 of the nozzle, causing a stream of compound to issue from the nozzle, and discharge into the curled flange of a can end, held in the rotating chuck below it, or it may be lowered, stopping the flow of compound, after the chuck has turned for more than one revolution, and filled the curled flange of the can end all around.

Can ends are generally provided with annular grooves and ridges for stiffening them, and the lower chuck 22 is formed with an oval groove 67 and a ridge 68 accordingly.

When the spider 74 comes to rest, the chuck 22 also comes to rest, with the major axes of the groove 67 and of the ridge 68 running in the same direction as the axes of the can ends in the stack, as shown in Figure 7.

The can end slide 54, which transfers the can ends from the magazine to the chuck 22, has the shoulders 93 so formed, as to maintain the can end axes in the same direction, as they were in the can end magazine, insuring the registration of the grooves and ridges of the can ends with those of the chuck, when the former are placed upon the latter.

After the slide 54 has moved a short distance on its return stroke towards the magazine, the chuck is raised, and then rotated for one and one half revolutions, while the slide moves to the end of the return stroke, the lugs 94 passing beneath the chuck.

While the chuck 22 together with the spindle 21 and the cam 24 rotate, the latter, being held by the spring 29 against the stationary roller 28, causes the swinging of the bifurcated arm towards or away from the tip of the nozzle, to an extent required to preserve the alignment of the nozzle with the groove in the can end flange.

After the chuck 22 has completed one and one half revolutions, the major axes of the

chuck will again be in the same direction as before starting, the oval being a symmetrical figure, and when lowered, will be in the proper position to receive another can end, 5 after the finished one has been removed by the lugs 94 of the slide 54.

The needle valve, controlling the discharge of lining compound into the flange of the can end, is operated by a cam 99, carried upon 10 the main driving shaft 40, and safety devices are interposed between said cam and the stem 8 of the needle valve, to insure the opening of the nozzle, when a can end to be lined is present upon the chuck 22, and to 15 keep the nozzle closed, if there is no can end upon the chuck to receive the compound.

For raising and lowering the needle valve there is provided a beam lever 100, fulcrumed at the middle upon a post 101, extending upwards 20 from an arm 102 of the bracket 7, said beam lever engaging at one end a collar 103, secured to the stem 8 of the needle valve, and carrying at the other end a rod 104, furnished at the lower end with a sleeve 105, 25 provided at its lower end with a tooth 106, projecting to one side of it, and at its upper end with a handle 107, whereby it may be given a turn. A bearing 108, secured to the frame 1, serves to guide the end of the rod 104. The rod is held in an upward position 30 by a spring 109, placed upon the stem 8 of the needle valve, engaging at the lower end the collar 103, and resting at the top against the guiding bracket 119, carried upon the 35 bracket 7.

The rod 104 is actuated by a cam 99, carried upon the main driving shaft 40, engaging a roller 120, mounted upon a pin carried upon one arm of a bell crank lever 121, pivoted at 40 122 to a bracket 123, while a tension spring 125, acting upon the other arm, tends to keep the roller in contact with the cam, oscillating the bell crank lever.

A hook bar 124 is pivoted to the bell crank 45 lever, said hook bar being adapted to swing towards the tooth 106, bringing the hook in alignment with said tooth, when a can end is present upon the chuck 22, or remain at rest, the hook being out of alignment with 50 the tooth, when there is no can end upon the chuck 22.

The hook bar 124 engages the tooth 106 during the downward motion of the arm 121, and pulling down upon the rod 104, causes 55 the lifting of the needle valve off its seat, discharging lining compound.

For actuating the hook bar 124, a feeler rod 126 is made to pass through the central opening 127 of the tubular stem 33, the lower 60 end of said rod extending downward beyond the chuck disc 32, while the upper end connects with a beam lever 128, fulcrumed upon a lug 129, provided upon the arm 30 and carrying at the other end a rod 130, which 65 passing through the inside of the tubular

shaft 12, rests upon the end 131 of a bell crank lever, fulcrumed upon a pin 132, secured to the frame of the machine.

In the operation of the machine, a can end to be lined is placed upon the lower chuck 70 22 and the chuck is raised, until it engages the upper chuck disc 32; the lower projecting end of the feeler rod 126 then comes in contact with the center of the can end and is raised, rocking the beam lever 128, and lowering the rod 130 and the arm 131 of the bell crank lever; the other arm 133 of the bell crank, connecting by means of the link 134 with the hook bar 124, swings said hook towards the sleeve 105, bringing it in alignment 75 with the tooth 106, ready to pull upon it, when the arm 121 swings downward, and thus open the needle valve.

In case no can end has been placed upon the chuck 22, the feeler rod 126 will not be 80 raised by the upward motion of the chuck, the projecting end of the feeler rod entering the hole 135, provided in the lower chuck, and the hook bar remaining out of alignment 85 with the tooth 106, as shown in Figure 6, will 90 fail in its downward motion to pull the rod 104 down and open the needle valve.

When it is desired to set the machine by hand, so as to prevent the opening of the needle valve controlling the discharge of lining compound, the tooth 106 is turned to one side and out of alignment with the hook bar 124 by means of the handle 107. The downward motion of the hook bar will not affect 95 then the sleeve 105 and the rod 104, and the 100 needle valve will remain closed.

For converting the machine from an arrangement lining can ends of one shape, into an arrangement for lining can ends of another shape, the can end magazine together with the can end feed slide and releasing bars, and the lower spindle 21 together with the lower chuck 22 and cam 24 are replaced by others conforming with the shape of the can 105 ends to be lined.

In transmitting rotary motion from the stationary mounted shaft 77 to the movably mounted spindle 21, a number of intermediate gears were used as shown in Figure 4.

When the arm carrying the spindle 21 115 swings towards or from the stationary roller, said swinging affects the rate of rotation of the spindle; the swinging of the arm against a clockwise direction tends to turn the gear 81 against a clockwise direction, turning the 120 gear 23 and the chuck in a clockwise direction.

The swinging of the arm thus adds to at one time and diminishes at another time the 125 uniform speed of the chuck.

Since it is desirable to rotate the chuck at a uniform rate of speed, in order to distribute the lining compound more evenly, the position of the tubular shaft in relation to the position of the chuck, when its major axis is 130

in a direction across the machine, is so chosen, as to place the bifurcated arm in a direction at an angle with said major axis of the chuck, as shown in Figure 4.

5 The path of travel of the spindle 21 will be not along the center line of the machine, but at an incline with it, the component part of the motion in the direction across the machine moves the can end flange in relation to 10 the stationary nozzle in the proper direction, and with substantially the proper amount to compensate for the disturbing effect of the swinging of the arm.

Having thus described my invention what 15 I claim as new and desire to secure by Letters Patent is:

1. In a machine of the character described a stationary lining compound nozzle, a rotatable chuck adapted to clamp an irregular 20 shaped can end having a flange for receiving lining compound movably mounted adjacent said nozzle, means for rotating said chuck, means for moving said chuck in a plane perpendicular to the jet of compound 25 issuing from said nozzle and in a direction towards and from said nozzle in order to keep said flange in alignment with said nozzle during the rotation of the chuck, and means controlling the discharge of lining compound 30 from said nozzle.

2. In a machine of the character described a stationary lining compound nozzle, a chuck adapted to clamp an irregular shaped can end movably mounted adjacent said nozzle, means 35 for imparting intermittent rotary motion to said chuck, means for moving said chuck in a plane perpendicular to the jet of compound issuing from said nozzle and in a direction towards and from said nozzle during 40 the rotation of the chuck, and means controlling the discharge of lining compound from said nozzle.

3. In a machine of the character described a stationary lining compound nozzle, a chuck 45 adapted to clamp a flanged irregular shaped can end movably mounted adjacent said nozzle, means for imparting intermittent rotary motion to said chuck starting with an accelerating velocity, then continuing with 50 a uniform velocity for one complete revolution, and terminating with a decelerating velocity until brought to a stop, means for keeping the can end flange in alignment with said nozzle during the rotation of the chuck, and means controlling the discharge of sealing compound from said nozzle.

4. In a machine of the character described a stationary lining compound nozzle, a chuck adapted to clamp an irregular shaped can 60 end movably mounted adjacent said nozzle, and means for imparting intermittent rotary motion to said chuck for one and one half revolutions, starting with an accelerating velocity, then continuing with a uniform velocity for one complete revolution, and ter-

minating with a decelerating velocity until brought to a stop, said means comprising a spider adapted to receive an intermittent rotary motion for a portion of one complete revolution with velocities accelerating at the start, then uniform in the middle portion, and terminating with decelerating, and a train of gears connecting said spider and said chuck, whereby the rate of rotation of the chuck is so increased, as to cause it to turn for one and one half revolutions, during the rotation of the spider through said portion of a revolution.

5. In a machine of the character described a stationary lining compound nozzle, a swinging arm pivoted at some distance from said nozzle, a chuck adapted to clamp an irregular shaped can end rotatably mounted upon said arm adjacent said nozzle, means for imparting intermittent rotary motion to said chuck, and means for swinging said arm during the rotation of said chuck.

6. In a machine of the character described a stationary lining compound nozzle, a swinging arm pivoted at some distance from said nozzle, a spindle mounted in bearings upon said swinging arm adjacent said nozzle, a chuck adapted to clamp an irregular shaped can end secured upon said spindle, a cam keyed to said spindle, a stationary pin, a roller mounted upon said stationary pin, a spring adapted to act upon said arm so as to keep said cam in contact with said roller, and means for rotating said spindle.

7. In a machine of the character described a stationary lining compound nozzle, a swinging arm pivoted at some distance from said nozzle, bearings provided upon the free end of said swinging arm adjacent said nozzle, a spindle mounted in said bearings, a chuck mounted upon said spindle, and means for rotating said spindle including a gear rotating around the pivot of said swinging arm, and means carried upon said arm operatively connecting said gear with said spindle.

8. In a machine of the character described a stationary frame, a table supported upon said frame, a lining compound nozzle, and a can end magazine both rigidly mounted upon said table, a can end chuck adapted to receive oscillatory motion in a plane perpendicular to the jet of compound issuing from said nozzle and in a direction towards and away from said nozzle for a predetermined period, and remain at rest at a definite point adjacent said nozzle for another period; can end releasing devices placed below said magazine adapted to release can ends at the bottom of the magazine, and drop them one by one upon said table, and a can end feed slide placed above the table, and adapted to engage the can ends dropped by the releasing devices, carrying them from beneath the magazine to said definite point and place them upon the chuck during said rest period.

9. In a machine of the character described a stationary frame, a table supported upon said frame, a lining compound nozzle, and a can end magazine adapted to guide a stack 5 of irregular shaped can ends, both rigidly mounted upon said table, a chuck provided with registering marks adapted to clamp an irregular shaped can end, means for imparting rotation to said chuck for a predetermined period, and for bringing it to rest for another period with the registering marks pointing in a definite direction, means for oscillating said chuck to and from said nozzle during the rotation of said chuck, and 10 means for removing a can end from said magazine and place it upon said chuck in register with said marks.

10. In a machine of the character described a stationary frame, a table supported upon 20 said frame, a lining compound nozzle rigidly mounted upon said table, a swinging arm pivoted to the frame, a spindle mounted in bearings upon said swinging arm in front of said nozzle, a chuck mounted upon said spindle, and means for rotating said spindle, said means including a gear revolving around the pivot of said swinging arm, and means carried upon said arm operatively connecting said gear and said spindle; the location of the pivot for the swinging arm being so chosen, as to cause the chuck in its travel away from said nozzle to move along a line deviating from the line joining said chuck and said nozzle by a small angle and in a 30 direction away from said pivot.

11. In a machine of the character described a stationary lining compound nozzle, a rotatable chuck mounted adjacent said nozzle, and means for imparting an intermittent rotary motion to said chuck, said means comprising: a spider mounted upon a shaft, rollers mounted upon the spider, a continuously revolving drive shaft, a cam secured upon said shaft fitting between two adjacent rollers 40 of said spider and adapted to advance the spider for a distance equal to the distance between two adjacent rollers during a portion of a revolution of the drive shaft, and to leave said spider at rest during the remainder of one complete turn, and a train of gears connecting said spider and said chuck, whereby the said advance of the spider imparts one and one half revolutions to said chuck.

12. In a machine of the character described 55 a stationary lining compound nozzle, a rotatable chuck mounted adjacent said nozzle, and means for imparting intermittent rotary motion to said chuck for one and one half revolutions, starting with an accelerating velocity, then continuing with a uniform velocity for one complete revolution, and terminating with a decelerating velocity until brought to a stop, said means comprising a shaft, a spider mounted upon said shaft, rollers mounted upon the spider, a continuously re-

volving drive shaft, a cam secured upon said shaft fitting between two adjacent rollers of said spider, and adapted to advance the spider for a distance equal to the distance between two adjacent rollers during a portion of a revolution of the drive shaft, and to leave said spider at rest during the remainder of one complete turn, the outline of said cam being such, as to remain in constant contact with said rollers during the motion of the spider and to advance said spider at a rate of speed accelerating, for a short distance at the start, uniform at the middle portion, and terminating with decelerating motion, and means connecting said spider and said chuck, whereby the said advance of the spider imparts one and one half revolutions to said chuck.

13. In a machine of the character described a stationary frame, a lining compound nozzle rigidly secured to said frame, a swinging arm mounted in bearings upon said frame, bearings provided upon the free end of said swinging arm adjacent said nozzle a spindle mounted in said bearings upon said arm, a can end chuck secured upon said spindle, means for rotating said spindle, and devices for sliding the spindle in its bearings, said devices comprising a lever pivoted at one end to said swinging arm engaging at the other end said spindle, a cam carried upon a drive shaft, a bell crank lever actuated by said cam, a link suspended from said lever carrying a roller riding upon one arm of said bell crank lever, and a spring for keeping said roller in contact with said bell crank lever.

14. In a machine of the character described a stationary frame, a lining compound nozzle rigidly mounted upon said frame, a pivoting shaft, a lower and an upper swinging arm secured to said shaft, a lower chuck and an upper chuck adapted to clamp a flanged irregular shaped can end rotatably mounted upon said swinging arms, means for rotating the chucks, means for keeping the flange of the can end in alignment with said nozzle during the rotation of the chucks, and means for discharging lining compound from said nozzle into the flange of the can end.

15. In a machine of the character described a stationary frame, a lining compound nozzle rigidly mounted upon said frame, a pivoting shaft, a lower and an upper swinging arm secured to said shaft, an upper chuck rotatably mounted upon the upper arm and held yieldingly thereon, a lower chuck rotatably mounted upon the lower arm, means adapted to place a flanged irregular shaped can end upon said lower chuck, means adapted to raise the lower chuck and bring it against the yielding upper chuck clamping the can end, means for rotating the said chucks, means for keeping the can end flange in alignment with the nozzle, and means for discharging

lining compound from said nozzle into the flange of the can end.

16. In a machine of the character described a stationary frame, a lining compound nozzle rigidly mounted upon said frame, a needle valve furnished with a stem and controlling the discharge of lining compound from said nozzle, a swinging arm mounted upon said frame, a lower chuck and an upper chuck adapted to clamp a flanged can end carried upon said arm, and means for discharging lining compound in the can end flange comprising a beam lever fulcrumed upon a stationary pin and engaging at one end said stem, and a cam actuated lever operatively connected with the other end of the beam lever.

In testimony whereof I affix my signature.
MARCUS S. LEVE.
